UNITED STATES PATENT OFFICE.

WILLIAM M. DUNCAN, OF ALTON, ILLINOIS.

MECHANICAL STOKER.

Application filed June 13, 1923. Serial No. 645,026.

This invention relates to improvements in stokers, and more particularly to a mechanical stoker provided with one or more draft boxes from which draft is discharged through the upper portion of an endless traveling grate.

Prior to this invention, mechanical stokers and especially stokers designed for forced draft have been provided with draft boxes open at the top to discharge draft through the fuel. In a stoker of this kind, ashes and fine particles of fuel drop through the upper portion of the grate and fall through the open top of the draft box. The removal of ashes, etc., from such draft boxes has been recognized as one of the difficult problems in this art, and various complex and expensive means have been employed to remove the ashes and fine fuel from the draft boxes. The old mechanically operated cleaning devices have not met with complete success, and the relatively simple manually operated cleaning means is undesirable on account of the time and labor involved in using the same.

Furthermore, the draft box should be sealed to prevent leakage of air under pressure at the outlet through which ashes and the like are discharged, and the sealing has heretofore been accomplished by relatively expensive means including large doors having accurately finished edges engaging correspondingly finished parts of the draft boxes.

One of the objects of the present invention is to produce an extremely simple and inexpensive draft box structure adapted to deliver a forced draft to the fuel. A further object is to provide for automatic removal of ashes and fine fuel from the draft box without adding any expensive element to the structure. Another object is to seal the draft box so as to prevent leakage of draft, and to accomplish this at a minimum cost, or without any appreciable addition to the cost of the apparatus.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends

changes, variations and modifications which come within the scope of the claims hereunto appended.

Briefly stated, the preferred form of the invention comprises a draft box surrounded by an endless traveling grate, the bottom wall of the box being seated on and supported by the traveling lower portion of the grate. This bottom wall has an outlet through which ashes and fine fuel are discharged into the lower portion of the grate, the latter serving to carry the material to a convenient discharge point. In this manner, the grate structure is utilized to clean the draft box.

The floating bottom wall of the draft box, resting upon a traveling portion of the grate, is spaced from the other walls, and the parts are so arranged that ashes, etc., serve as means for closing the spaces. The apparatus is also designed to prevent leakage of draft at the outlet through which ashes, etc., are discharged from the bottom wall. This wall preferably rests upon the lower portion of the grate, and the fine material discharged into this part of the grate serves as a seal to prevent leakage of draft through the outlet. As a further safeguard, a sealing plate is preferably located below the draft box where it contacts with the lower portion of the traveling grate to support the same and at the same time confine the ashes below the draft box where they serve as a seal for the ash outlet in the floating bottom wall. By combining the several elements as herein pointed out the structure is rendered self-cleaning and self-sealing, and this is accomplished in a draft box structure which is evidently simpler and less expensive than the ordinary structures without the mechanical sealing and cleaning features.

Fig. I is a longitudinal section illustrating a mechanical stoker embodying the features of this invention.

Fig. II is a transverse section taken approximately on the line II-II in Fig. I.

To illustrate the invention I have shown a portion of a furnace provided with side walls 1 between which the stoker is mounted on wheels 2. The stoker comprises side frames 3 in which the wheels 2 are mounted, an endless chain grate 4 between the side frames, the usual drive wheels 5 mounted

on a power shaft 6 at the front ends of the side frames, and the usual idle roll 7 at the rear of the side frames. The shaft 6 can be driven by any suitable means to cause the 5 upper portion of the grate to travel toward the rear of the furnace, while the lower portion of the grate moves toward the front. 8 designates a fuel hopper located at the front of the stoker to discharge fuel onto 10 the top of the traveling grate.

Partitions 9, surrounded by the endless 15 grate, are connected by means of bars 10 to the side frames 3 so as to form the side walls of a series of draft boxes. The end walls 15 of these boxes are formed by the side frames 3 which support the partitions 9.

The bottom walls of the several draft 20 boxes are formed by a long plate 11 located below and separated from the lower edges 20 of the partitions 9. The plate 11 is approximately as wide as the grate, but its side edges are preferably separated a slight distance from the side frames 3, as it would be difficult and expensive to closely fit the plate 25 to the side frames. Instead of being attached to the side frames or to the partitions 9, the plate 11 rests upon and is supported by the lower portion of the traveling chain 30 grate. To aid in forming ash seals which will be hereafter described, and also to limit the motion of plate 11, angle bars 12 are riveted to said plate, and the upper margins of some of these angle bars are arranged to engage abutments formed by the lower edges 35 of partitions 9. It is not necessary for all of the bars 12 to engage partitions 9.

A forced draft may be supplied through 40 a conductor 13 (Fig. II) at one side of the furnace, each draft box being provided with telescoping intake tubes 14 and 15 extending from said conductor to one of the side frames. The draft forced into the draft 45 boxes is permitted to pass out through the open upper sides thereof, and thence through the upper portion of the grate to the fuel supported thereon.

Ashes and fine fuel drop through the upper portion of the chain grate and fall onto the long plate 11 which forms the bottoms 50 of the draft boxes. This plate has outlet openings 16 through which the ashes, etc., are discharged into the lower portion of the traveling grate. In actual practice, the ashes will usually lie in angular piles as suggested in the drawings, each pile being inclined downwardly toward a discharge opening 16. The openings 16 may be narrow, but they are preferably elongated as shown by Fig. II, so as to extend almost entirely from end to end of the draft boxes.

I will now point out the manner in which the draft boxes may be sealed to prevent leakage of draft at their lower corners. The partitions 9 terminate above the bottom plate 11, but the piles of ashes and fine fuel

accumulate at the partitions to form seals preventing leakage of draft through the spaces below said partitions. This is accomplished by locating the discharge openings 16 at points remote from the partitions 9, 70 and the seals are rendered more effective by the angle bars 12 serving as baffles for the ashes. As a further safeguard, Z-bars 17 may be secured to partitions 9 so as to form inverted pockets in which the upper edges 75 of angle bars are arranged. The baffles produced in this manner serve to confine ashes, etc., which form seals to prevent escape of draft. I have shown the Z-bars 17 on the partitions 9 at the rear portions of the 80 grate where the ashes are relatively fine and more likely to be blown through the spaces between bars 12 and partitions 9.

The side edges of bottom plate 11 are separated from the side frames 3, and these 85 frames extend downwardly to points beyond said bottom plate, as shown in Fig. II. Angle bars 18 are secured to the side frames so as to overlie the spaces at the side edges of the bottom plate 11, and these bars serve 90 as baffles preventing free escape of ashes and fine fuel at said spaces. This results in the production of seals at the lower end corners of the draft boxes.

The lower portion of the traveling chain 95 grate is supported by a long plate 19 resting upon rods 20 which extend through the side frames 3, and longitudinal motion of this plate is prevented by lugs 21 extending from the plate and engaging two of the rods 20, 100 as shown in Fig. I. The plate 19 lies directly below plate 11 and it extends from the front to the rear of the grate. It also extends from one side frame 3 to the other.

In addition to serving as a substantial 105 support for the lower portion of the flexible chain grate, the plate 19 cooperates with the plate 11 to form a passageway through which the grate travels. The ashes and other material discharged through openings 16, at the bottoms of the draft boxes, enter into this passageway and are carried to the front of plate 19 where they are permitted to drop from the chain grate. The plate 19 may be termed a sealing plate, for 110 it confines the ashes, etc., in the chain grate so as to form a seal which prevents any material leakage of draft through the openings 16 where the ashes and fine fuel are discharged from the draft boxes.

The upper portion of the chain grate may be supported by long bars 23 resting upon the upper edges of partitions 9, and also by angle bars 24 secured to the partitions.

I claim:

1. A mechanical stoker comprising an endless traveling chain grate, a draft box surrounded by said traveling grate, the top of said draft box being open to discharge draft through the upper portion of said 130

grate, and the bottom wall of said draft box being in contact with and supported by the lower portion of said traveling grate.

2. A mechanical stoker comprising an endless traveling chain grate, a draft box surrounded by said traveling grate, the top of said draft box being open to discharge draft through the upper portion of said grate, and the bottom wall of said draft box being in contact with and supported by the lower portion of said traveling grate, and abutments limiting the motion of said bottom wall.

3. A mechanical stoker comprising an endless traveling chain grate, a draft box surrounded by said traveling grate, the top of said draft box being open to discharge draft through the upper portion of said grate, and the bottom wall of said draft box being in contact with and supported by the lower portion of said traveling grate, said bottom wall being arranged to receive the material falling through the upper portion of the grate and provided with an outlet for the discharge of said material into the lower portion of the traveling grate.

4. A mechanical stoker comprising an endless traveling chain grate, a draft box surrounded by said traveling grate, the top of said draft box being open to discharge draft through the upper portion of said grate, and the bottom wall of said draft box being in contact with and supported by the lower portion of said traveling grate, said bottom wall being spaced from the side walls of the draft box and the draft box being provided with means to prevent free escape of ashes at the spaces.

5. A mechanical stoker comprising an endless traveling chain grate, a draft box surrounded by said traveling grate, the top of said draft box being open to discharge draft through the upper portion of said grate, and the bottom wall of said draft box being in contact with and supported by the lower portion of said traveling grate, said bottom wall being spaced from the side walls of the draft box and the draft box being provided with baffles to prevent free escape of ashes at the spaces.

6. A mechanical stoker comprising an endless traveling chain grate, a draft box surrounded by said traveling grate, the top of said draft box being open to discharge draft through the upper portion of said grate, and the bottom wall of said draft box being in contact with and supported by the lower portion of said traveling grate, said draft box having end walls extending downwardly beyond said bottom wall, said end walls being spaced from said bottom wall and provided with means to prevent free escape of ashes at the spaces.

7. A mechanical stoker comprising an endless traveling chain grate, a draft box

surrounded by said traveling grate, the top of said draft box being open to discharge draft through the upper portion of said grate, and the bottom wall of said draft box being in contact with and supported by the lower portion of said traveling grate, said bottom wall being located entirely below the side walls of the draft box and interposed between the end walls thereof, said bottom wall being spaced from said side and end walls and the draft box being provided with baffles to prevent free escape of ashes at the spaces.

8. A mechanical stoker comprising an endless traveling chain grate, draft boxes surrounded by said traveling chain grate, the top of each draft box being open to discharge draft through the upper portion of said grate, and a continuous plate forming the bottom walls of said draft boxes, said plate being in contact with and supported by the lower portion of said traveling grate.

9. A mechanical stoker comprising an endless traveling chain grate, draft boxes surrounded by said traveling chain grate, the top of each draft box being open to discharge draft through the upper portion of said grate, and a continuous plate forming the bottom walls of said draft boxes, said plate being in contact with and supported by the lower portion of said traveling grate, said plate being arranged to receive the material falling through the upper portion of the grate and provided with an outlet in each draft box for the discharge of said material into the lower portion of the traveling grate.

10. A mechanical stoker comprising an endless traveling chain grate, a draft box surrounded by said traveling grate, the top of said draft box being open to discharge draft through the upper portion of said grate, the bottom wall of said draft box being arranged to receive material falling from the upper portion of the grate, said bottom wall being adjacent to the lower portion of the traveling grate and provided with an outlet for the discharge of said material into said lower portion, and a sealing plate located directly below the draft box and in contact with the bottom face of the grate so as to support the outgoing material below the draft box, said bottom wall being seated on and supported by the lower portion of the traveling grate, and said lower portion being supported by said sealing plate.

11. A mechanical stoker comprising an endless traveling chain grate having a fuel-supporting upper portion, a lower portion directly below said upper portion, a part of said lower portion being exposed to receive granular material dropping from the fuel, an air chamber being formed between

said upper and lower portions to provide for the admission of draft to the fuel, sealing means at the lower corners of said chamber to confine the draft therein, said sealing means including baffles arranged longitudinally of the grate and located above and adjacent to the side margins of said lower portion to obstruct the granular material, and baffles arranged transversely of the ¹⁰ grate and extending from one of said side

margins to the other, said baffles being adapted to cooperate with the granular material to form the seals in said lower corners, and sealing means located below and in contact with the lower portion of the ¹⁵ grate to prevent free escape of draft through said lower portion.

In testimony that I claim the foregoing I hereunto affix my signature.

WILLIAM M. DUNCAN.
